ROBERT McCONNELL.

UNITED STATES PATENT OFFICE.

JAMES PHIPPS, OF PHILADELPHIA, PENNSYLVANIA, ASSIGNOR TO MARTIN LANDENBERGER & CO., OF SAME PLACE.

DESIGN FOR A NUBIA.

Specification forming part of Design No. **6,710**, dated June 17, 1873; application filed May 17, 1873.

To all whom it may concern:

Be it known that I, JAMES PHIPPS, of Philadelphia, county of Philadelphia, State of Pennsylvania, have invented a Design for Nubia, of which the following is a specification:

The figure in the accompanying drawing clearly illustrates my design for a nubia, the principal features of which are the border A, and stripe or stripes B, upon a ground work D, of plain open-knitted loops of the character commonly used for nubias.

The border A is composed of a series of waved or scalloped threads *a*, preferably coarser than the threads of the body of the fabric, and interlocked with the latter as

shown. The stripe B, which may be of any desired width, and of which there may be one or more between the borders, is similarly composed of waved or scalloped threads *a*.

Inspecting of the colors employed, I claim—

The design for a nubia, substantially as described, and as represented in and by the accompanying drawing.

In testimony whereof I have signed my name to this specification in the presence of two subscribing witnesses.

JAMES PHIPPS.

Witnesses:

H. DORNEMANN,
ROBERT McCONNELL.
